UNITED STATES PATENT OFFICE.

SAMUEL K. ANDERSON AND JOHN LONG, OF SOUTH AUBURN, NEBRASKA.

POLE-TIP.

1,072,296.

Specification of Letters Patent.

Patented Sept. 2, 1913.

Application filed December 2, 1912. Serial No. 734,570.

To all whom it may concern:

Be it known that we, SAMUEL K. ANDERSON and JOHN LONG, residing at South Auburn, in the county of Nemaha and State 5 of Nebraska, have invented certain new and useful Improvements in Pole-Tips; and we do hereby declare the following to be a full, clear, and exact description of the invention, such as will enable others skilled in the 10 art to which it appertains to make and use the same.

This invention relates to tips for draft poles or tongues for all kinds of vehicles and agricultural implements; and it consists 15 of a split clamping collar provided with tongues and secured to the pole as herein-after fully described and claimed.

In the drawings, Figure 1 is a side view of a portion of a draft pole provided with a 20 tip according to this invention. Fig. 2 is a plan view of the same; and Fig. 3 is an end view.

The front end portion 2 of the draft pole is provided with a split clamping collar 3 25 having lugs 4, and 5 is a clamping bolt which passes through holes in the lugs and clamps the collar after it has been slid to a suitable position on the pole.

The collar is provided with a split tongue 30 7 which projects from it longitudinally and in line with its lugs. The collar has also a tongue 8 which projects from the opposite side of it from the split tongue and in the opposite direction.

Both tongues 7 and 8 are shaped to fit 35 against the pole, and fastening screws 9 may be inserted if desired, but these screws are not usually necessary.

The upper tongue prevents the neck-yoke from wearing away the wood of the draft 40 pole, and the lower tongue prevents the neck-yoke ring from wearing away the wood of the pole. These pole tips are made of any suitable metal, and in sizes adapted to different kinds of draft poles. 45

What we claim is:

1. A tip for a draft pole, comprising a split collar adapted to be clamped on the pole and having tongues projecting longitudinally from it in opposite directions and 50 arranged upon opposite sides of its axis.

2. A tip for a draft pole, comprising a split collar provided with lugs and a split tongue on one side of its axis and adapted to be clamped to the pole and having a 55 tongue on the other side of its axis, said tongues projecting longitudinally from it in opposite directions.

In testimony whereof we affix our signatures, in presence of two witnesses.

SAMUEL K. ANDERSON.
JOHN LONG.

Witnesses:

LESTER FOX,
W.M. CAIRNS.
